UNITED STATES PATENT OFFICE

CHARLES E. CHADWICK, OF SYRACUSE, NEW YORK.

DESIGN FOR A VEHICLE-SPRING.

SPECIFICATION forming part of Design No. 19,732, dated April 1, 1890.

Application filed November 22, 1889. Serial No. 331,256. Term of patent 14 years.

To all whom it may concern:

Be it known that I, CHARLES E. CHADWICK, a citizen of the United States, residing at Syracuse, in the county of Onondaga and State of New York, have invented and produced a new and original Design for Vehicle-Springs Adapted for Two-Wheeled Carts, of which the following is a specification, reference being had to the accompanying drawing, forming a part thereof.

10 The drawing is an elevation of my design, one view being deemed sufficient to illustrate the same.

The leading feature of my design consists 15 in a central depressed plane, a rearward upwardly-curving plane having its extremity above said depressed plane, and a forward gradual upwardly-curving plane having its extremity above said depressed plane and beneath the upward extremity of the rear upwardly-curving plane.

A represents the centrally-depressed plane disposed in substantially a horizontal plane.

B represents the rear upwardly-curving 25 plane, composed of the rearwardly-extending

part b and the forwardly-extending portion b', with the extremity of said parts b' elevated above the said depressed plane A.

C represents the forward upwardly-curving plane, having its extremities c elevated above 30 the depressed planes A and below the extremity of the rear upwardly-curving plane B.

This combination of curves in different planes and of different degrees presents a very pleasing and effective appearance to the 35 eye and causes the spring to have a constant change in plane, thus producing a very desirable design.

What I claim is—

The design for a spring for carts herein 40 shown and described.

In testimony whereof I have hereunto signed my name, in the presence of two attesting witnesses, at Syracuse, in the county of Onondaga, in the State of New York, this 45 19th day of April, 1889.

CHARLES E. CHADWICK.

Witnesses:

CLARK H. NORTON,
A. E. PARSONS.
